UNITED STATES PATENT OFFICE.

HENRY DREYFUS, OF BASEL, SWITZERLAND.

CELLULOSE ACETATES AND PROCESS OF MAKING SAME.

14,338.

Specification of Reissued Letters Patent. Reissued July 31, 1917.

No Drawing. Original No. 1,181,857, dated May 2, 1916, Serial No. 652,442, filed October 2, 1911. Application for reissue filed October 19, 1916, Serial No. 126,502.

To all whom it may concern:

Be it known that I, HENRY DREYFUS, a citizen of the Republic of Switzerland, residing at Basel, Switzerland, have invented 5 certain new and useful Improvements in Cellulose Acetates and Processes of Making Same, of which the following description is a specification.

The present invention relates to cellulose 10 acetates having special properties, and the methods whereby such acetates are produced.

The known processes of making cellulose acetates mostly depend upon the selection 15 of the particular condensing agent to be employed. The greater part of the patents assume that sulfuric acid is highly injurious on account of its great splitting action on cellulose. Accordingly various substitutes 20 therefor have been proposed, such as hydrochloric, nitric, nitrosulfuric acids, or salts such as zinc chlorid, sodium bisulfate, sulfonic acids, chloracetic acid, etc. In some of these processes, either cellulose or hydro- 25 cellulose may be employed, *e. g.* that produced by the Girard process, using sulfuric acid of 3% strength, or by using sulfuric and glacial acetic acid. Other processes use moist cellulose to avoid splitting of the 30 cellulose. Each of these processes is said to have its own special advantages, and with the process using sulfuric acid, etc., and glacial acetic acid, solutions are obtained 35 which have more or less viscosity, or limpidity, according to the exact procedure followed.

The products heretofore produced, have been in nearly all cases soluble in chloroform, and in glacial acetic acid. Films 40 made therefrom have been either stretchy, brittle or otherwise objectionable, rendering them practically useless for most purposes.

In my present invention I have found a 45 process for the direct manufacture, by a direct acetylation process of cellulose acetates insoluble in chloroform, but soluble in a mixture of chloroform and alcohol, which acetates are also insoluble in diluted or concentrated alcohol. Some of these products are soluble in pure acetone, others are distinguished by a characteristic behavior upon 50 treating them with pure acetone. They become transparent or semi-fluid and plastic 55 therein, and by the addition of a small quan-

60 tity of water, they produce viscous solutions. In carrying out this process, there is no intermediate stage, in which the cellulose acetates become soluble in chloroform. I have found that the manufacture of these 65 products depends upon a series of conditions, which must be present in carrying out the reaction. Thus the production of this result depends upon the simultaneous control, relatively to each other, of the temperature employed in the reaction, the humidity or amount of moisture present in the 70 cellulosic material employed, the amount of condensing agent employed, and the quantity of acetylating agent relatively to the 75 weight of cellulose used. These are some of the factors which are in mutual dependence with each other, and which determine the properties of the cellulose acetates produced in carrying out the process.

I have found that, in the preparation of 80 such acetates, sulfuric acid as the condensing agent, is perfectly satisfactory, provided that certain precautions are observed, as follows:—1, in carrying out the process 85 at a temperature not above 40° C., and preferably at ordinary room temperature, or by cooling to a lower temperature; 2, in employing the proper quantity of the acetylating agent; 3, in employing the proper 90 quantity of the condensing agent; 4, the selection of a cellulosic material (cellulose, hydrocellulose or partially acetylated cellulose) containing the proper amount of moisture.

95 My new process depends (among other conditions) upon carrying out the process of acetylation at or below ordinary room temperature, that is up to about 30° C., and upon employing particular proportions of acetic anhydrid or acetyl chlorid, and of sulfuric acid or other condensing agent; both as compared with the amount of cellulose, and also depending upon the amount 100 of moisture present in the cellulose, or other cellulosic body. These conditions depend upon each other, and determine the properties of the resulting products. If 10% of sulfuric acid, based on the weight of cellulose, is used, the amount of acetic anhydrid 105 used can be varied between about 1.5 and 3 kg. (preferably 1.8 kg. to 3 kg.) to each kilo of cellulose or cellulose derivatives. If more than 10% of sulfuric acid, say up to 20%, be employed, then (in addition to the 110

1.5 to 3 kg. of acetic anhydrid above referred to, per kg. of cellulosic material) there will be used an additional quantity of acetic anhydrid, up to about four times 5 the excess of sulfuric acid used, over and above the 10% above mentioned. These figures are based on using sulfuric acid 95 to 100% strength, pure acetic anhydrid, and cellulose containing 5 to 6% of moisture, 10 and working at ordinary room temperature. If the cellulose used contain more or less than this amount of moisture, the amount of acetic anhydrid will be increased or diminished accordingly.

15 Using 10% of sulfuric acid, and 3 kg. of acetic anhydrid, per kilo of cellulose containing 5 to 6% of moisture and keeping the reacting materials at or below ordinary room temperature, products extremely soluble in 20 alcohol-chloroform, but insoluble in chloroform alone, will be produced. I have also found that if it is desired to use a larger amount of sulfuric acid, the amount of moisture in the cellulose to be employed 25 should be decreased, otherwise insoluble, pasty or mucilaginous products will be obtained. If 20% or more of sulfuric acid is to be used the cellulose should preferably be dry, for example cellulose having been dried 30 at 25 to 50° C., in a dry room, and this is especially to be followed, if the cellulose, before acetylation, is treated with a mixture of sulfuric and glacial acetic acid. It is not advisable to too much hydrolyze the cellulose 35 before the introduction of acetic anhydrid or other acetylizing agents. Using cellulose containing 5% of moisture it is preferable to introduce it directly into a mixture of glacial acetic acid, acetic an- 40 hydrid and sulfuric acid.

If as much as 25% of sulfuric acid is to be used, dry cellulose should preferably be used, and it should be directly added to the above described mixture, otherwise a gelatinous product more or less easily soluble in 45 dilute alcohol or hot water will be produced.

I have found, that in order to cause the acetylation to take place in a regular manner, it is preferable to add the acetic an- 50 hydrid, or other acetylizing agent, to the mixture of glacial acetic acid, sulfuric acid and cellulose, while constantly stirring the reacting mass. For the manufacture, in one operation, of products having a very great 55 solubility, the amount of sulfuric acid should be between about 10 and 20% of the weight of the cellulose used, and the above proportions between the sulfuric acid, moisture content of the cellulose and acetic anhydrid 60 should be rather closely followed. In this manner one can obtain products which are capable of producing very concentrated solutions of cellulose acetates in alcohol-chloroform or alcohol-tetrachlorethane and which 65 can be used directly in the manufacture of

celluloid, etc. These cellulose acetates can also be produced in suspension by using appropriate indifferent diluents. The resulting products are also distinguished from the cellulose acetates heretofore known, by their 70 insolubility in chloroform and by their great solubility in alcohol-chloroform.

In order to carry out my process, dry cellulose, or cellulose with a moisture content of say about 5%, or cellulose previously 75 treated with diluted sulfuric acid (and dried down to about 5% of moisture,) or with a mixture of glacial acetic and sulfuric acids, or a hydro-cellulose (provided the latter is not too much decomposed), may be used. 80 It is evident that the afore-mentioned proportions between the moisture content, amount of sulfuric acid, the amount of acetylizing agent and temperature must be closely followed. By this energetic hydration, that is to say by the preceding hydration at low temperatures for example by the treatment with sulfuric and glacial acetic acids, it is to be noted that the cellulose molecule will not be destroyed or depolymerized 85 but it is possible to produce these more or less stiff solutions, of a viscosity which never could be produced by any of the processes previously known. I call attention to the fact that when this treatment at low temperature is continued for some time, there is no danger of depolymerization of the cellulose molecule during the acetylation step. 90

Also the low temperature at the commencement of the acetylation, does not have any 100 disadvantageous effect, apparently since the entering acetyl groups have a protecting influence upon the cellulose molecule. That the hydration at low temperatures does have a protecting effect is apparently due to the 105

fact that in the hydration or treatment during and after the introduction of the cellulose into the acetylizing mixture at, or preferably below, ordinary room temperature, the temperature does not rise much above 110 this point. In accordance with my invention, however, I have found that only those

cellulose acetates which are substantially insoluble in chloroform, but which become readily soluble by the addition thereto of more or less alcohol, (some of which cellulose acetates are readily soluble in acetone, and others of which are very soluble in diluted acetone containing a small amount of water,) are of value for the production, (by further transformation) of products having useful solubilities, and other useful properties. These are produced in the present invention, in observing the conditions of temperature, 115 quantity of sulfuric acid, quantity of acetic anhydrid and the like, relative to each other. 120

In accordance with my invention, by directly introducing the cellulose, and maintaining the materials at or below ordinary room temperature, unless observing the con- 125

ditions above pointed out, there will be obtained only syrupy products, which contain cellulose acetates readily soluble in chloroform, and which also contain a large quantity of unchanged fibers. Such products are not of value for the production of celluloid and films.

In order to obtain valuable products, the temperature during the introduction of the cellulose, and up to the completion of the reaction, must in every case be kept down. In operating in this manner, syrupy liquids are not obtained, but solutions of the highest viscosity, which do not contain a large quantity of unchanged fibers, and accordingly the products produced in accordance with my process are transparent, and give in the acetylating solution, very viscous products which may even approach a stiff or gelatinous mass. These products and especially their transformation products, give solutions of the highest viscosity, which products can therefore be employed in the celluloid and film industries.

In order to obtain rapidly a highly viscous solution, approaching in consistency a clear, stiff gelatinous mass, in accordance with my present invention, it is necessary to use very low temperatures. A product insoluble in chloroform, together with a high viscosity can be obtained (while using sulfuric acid alone as the condensing agent) if the temperature is not allowed, even in approaching the end of the acetylation, to approach 40° C., and the temperature during the entire process is preferably kept at or below ordinary room temperature to secure the best results. But in connection with this, I call attention to the fact that the products of the present invention are not intermediate products produced in the processes heretofore employed for the production of chloroform-soluble cellulose acetates, since in observing the conditions above stated to be necessary in my process, syrupy solutions will never be obtained. In many instances, at the end of the acetylizing reaction, there will be present clear, very viscous solutions, or clear gelatinous masses, of such a high viscosity that they are scarcely movable or are wholly immovable, that is to say they congeal from their acetylation solutions, so that they can be pulverized. Such products can not be produced if the cellulose is introduced into an acetylizing mixture of which the temperature is above ordinary room temperature, and if sulfuric acid is used as the condensing agent.

I again call attention to the fact that the present invention does not depend upon the temperature and the quantity of sulfuric acid alone, but upon these factors in connection with the amount of moisture in the cellulose employed, and this latter has to be taken in consideration. In a general way

the greater the amount of moisture present in the cellulose employed, the smaller must be the quantity of condensing agent to be employed, and all the above factors must be kept in mutual dependence one upon the other. In using a cellulose containing about 5 to 6% of moisture, better results are secured than with a dry cellulose, since with a dry cellulose the reaction goes on much more slowly, and in connection therewith other inconveniences result, for example that the viscosity of the solution does not appear until the last moment, when a clear solution or clear mass is obtained.

In accordance with my invention it is further necessary to use a quantity of an acetylating agent, such as acetic anhydrid, preferably not more than three times, and it is best to use only about two and one-half times the weight of the cellulose employed, since the excess of acetylating agent makes it more difficult to observe the preferable temperature, and makes it also more difficult to interrupt the reaction at the proper time. If smaller quantities of sulfuric acid as a condensing agent have been used, it is easier to regulate the temperature but the reaction does not go on so energetically. It is always necessary to employ a certain minimum quantity of sulfuric acid, relatively to the weight of cellulose used, in order to obtain technically valuable products. Accordingly the quantity of sulfuric acid can not arbitrarily be changed, but can be changed only according to the other conditions present in the reaction, (e. g. amount of moisture, etc.). The most favorable results for obtaining these cellulose acetates, insoluble in chloroform are obtained especially by the direct introduction of the cellulose into the acetylating mixture of for example glacial acetic acid, acetic anhydrid, and sulfuric acid, if one employs between 10% and 20% of sulfuric acid (and with advantage not under 5%) calculated upon the weight of the cellulose employed. In this case one obtains products, some of which are easily soluble in such solvents as concentrated acetone, and others in somewhat diluted acetone, which products, by their further transformation (for example in a precipitated form) give other solubilities.

The products, obtained by my process are distinguished in that while they are insoluble in chloroform, or in tetrachlorethane they can be dissolved to produce very concentrated solutions in alcohol-chloroform, or in alcohol-tetrachlorethane, etc., which was not possible with the products heretofore produced by any direct process.

The products obtained in my process are especially distinguished from those previously produced, by their great stability which is also true of the articles made therefrom, by their being substantially insoluble

in chloroform, and by their property of being able to give highly concentrated and viscous solutions of cellulose acetates, in alcohol-chloroform or in alcohol-tetrachloroethane (mixtures of, say, equal volumes of alcohol and chloroform, or alcohol and tetrachlorethane, respectively).

Those products which are completely or partially soluble in alcohol-benzin and other 10 solvents, are of particular interest.

In order to illustrate my invention I give the following examples, the parts being by weight, but it is to be noted that the invention is not limited to these examples.

15 Example I: 200 parts of cellulose, for example cotton containing about 5% of moisture, are treated with a mixture of 800 parts of glacial acetic acid and 20 parts of concentrated sulfuric acid. Into this mixture while 20 constantly stirring, and at ordinary room temperature, or by cooling, 400 parts of acetic anhydrid are slowly added. This addition may be made at once or after 2 or 3 hours or more. As soon as the material 25 dissolves, water may be added, while constantly stirring, to precipitate the cellulose acetate which is then washed, pressed, and dried. This product is insoluble in chloroform but 30 swells therein, it is soluble giving highly concentrated and viscous solutions in alcohol-chloroform or in alcohol-tetrachlorethane, etc., (these solvents for example being composed of equal volumes of the two liquids). The product shrinks in pure acetone 35 and forms a transparent, semifluid mass which by the addition of a small amount of water produces a viscous solution. Without precipitation by water the solution obtained by acetylation can also be employed directly 40 or after neutralization of the mineral acid for the manufacture of artificial silk, or other threads or for other purposes.

Example II: 200 parts of cotton having a moisture content of about 5% are treated 45 in the same manner with the mixture of 800 parts of glacial acetic acid and 20 parts of concentrated sulfuric acid. Directly, or after two to three hours approximately 600 parts of acetic anhydrid are added, while 50 constantly stirring and while preventing any substantial rise in temperature, the product is a viscous solution similar to that produced in Example I which can be worked up in the same manner. If desired the cellulose 55 can also be directly introduced into the acetylizing mixture while observing the above described temperature conditions. The resulting product shows a similar behavior, but in the latter case it may also be soluble 60 in pure acetone.

Example III: 200 parts of dry paper, such as is used in the manufacture of nitro-cellulose for celluloid, are treated with a mixture of 800 parts of glacial acetic acid 65 and 40 parts of concentrated sulfuric acid,

and after 2 or 3 hours 650 to 700 parts of acetic anhydrid are introduced, preferably while the mixture is maintained at or below ordinary room temperature, and while stirring. A product is obtained similar to that 70 of Example II, and is worked up in the same manner.

In these examples, the cotton or paper may be replaced by other forms of cellulose, or by their products of transformation. 75 Commercial sulfuric acid, glacial acetic acid, and acetic anhydrid can be used, of which the strength varies more or less or other acetylizing or diluting agents may be employed.

The proportions of sulfuric acid, glacial acetic acid, acetic anhydrid, and cellulose should not be greatly varied. The amount of moisture in the cellulose may vary somewhat. The cellulose esters may be separated 85 or precipitated from their solutions in any appropriate manner.

In a very advanced reaction with acetylation solutions, being more movable or more fluid, the precipitated acetate after 90 drying, becomes fluid in chloroform, without dissolving therein. The same remarks apply generally to tetrachlorethane, as to chloroform, but upon addition of more or less alcohol, either to the chloroform or 95 the tetrachlorethane, the cellulose acetate readily dissolves to produce a viscous solution, according to the duration of the reaction, and it becomes increasingly soluble in concentrated or diluted acetone. 100

The solubilities of the product, during this second reaction will successively change, depending upon the conditions present. The product, at the end of the acetylation reaction being soluble in a mixture of alcohol and chloroform (equal parts, for example), the solubility in such solvent successively increases; in relatively concentrated acetone, the solubility increases up to a certain maximum, and then commences to decrease, while the solubility in any more dilute acetone continues to increase up to a certain maximum (coming later than the maximum solubility in more concentrated acetone). A solubility in chloroform alone 115 may be developed, reach a maximum of ready solubility, and decrease, before reaching the maximum solubility in acetone, or the solubility in chloroform may not be developed at any stage of the process so that 120 the product remains always insoluble in chloroform depending upon the particular conditions and procedure. A solubility in a mixture of alcohol and benzene and in diluted alcohol will begin, approach a maximum and then begin to fall, before the maximum solubility in concentrated acetone is reached.

The process of altering the solubilities by the further treatment with acid solutions, 130

and the products of such treatment, are claimed in my copending applications 782, 530 filed August 1, 1912 (Patent No. 1,217, 722, dated Feb. 27, 1917) and 73,496 filed 5 January 21, 1916.

What I claim is:

1. A process of directly producing cellulose acetates substantially insoluble in chloroform, and insoluble in alcohol, but readily soluble in alcohol-chloroform, which comprises reacting upon cellulose with sulfuric acid and acetic anhydrid in proportions of about 10 parts of cellulose, not more than $2\frac{1}{2}$ parts of sulfuric acid, and about 15 to 30 10 parts of acetic anhydrid, at a temperature not above 40° C.
2. A process of directly producing cellulose acetates, insoluble in chloroform and in alcohol, but soluble in chloroform-alcohol, which comprises reacting upon cellulose with sulfuric acid and acetate anhydrid in proportions of about 10 parts of moist cellulose, about 1 part of sulfuric acid, and about 15 to 30 parts of acetic anhydrid, at a temperature not above room temperature.
3. A process of directly producing cellulose acetate substantially insoluble in chloroform which comprises treating 200 parts of cellulosic material containing about 5% 30 of moisture with a mixture of glacial acetic acid and about 20 parts of sulfuric acid, then adding, while stirring, and while not above ordinary room temperature about 400 parts of acetic anhydrid, then after the 35 cellulose has been transformed into acetates which have gone into solution, precipitating by adding the reaction mixture to water while stirring, separating the precipitated cellulose acetates, and drying the same.
4. A process of directly preparing cellulose acetates substantially insoluble in chloroform and in alcohol but readily soluble in alcohol-chloroform, which comprises treating a cellulosic material containing about 5 to 6% of moisture with not less than $1\frac{1}{2}$ 45 times its weight of an acetylizing agent, at a temperature below about 40° C., in the presence of not more than about 10% of its weight of sulfuric acid as a condensing 50 agent.
5. A process of directly preparing a class of cellulose esters which are insoluble in chloroform and insoluble in alcohol, but which are readily soluble in chloroform-alcohol, which comprises treating 100 parts of a cellulosic material with a mixture including from 150 to 300 parts of acetic anhydrid and a condensing agent corresponding to about 10 parts of sulfuric acid, said reaction 55 being performed at a temperature maintained lower than 40° C.
6. A process of making cellulose acetates which comprises reacting upon cellulose with sulfuric acid and acetic anhydrid in proportions of about 10 parts of cellulose, 65 about 1 part of sulfuric acid, and about 15 to 30 parts of acetic anhydrid, at a temperature maintained lower than 40° C., in the presence of a liquid material capable of diluting the liquid reagents employed, but incapable of preventing the acetylizing action upon the cellulosic material.
7. The process of making cellulose acetates substantially insoluble in chloroform and in alcohol, but readily soluble in alcohol-chloroform, which comprises introducing 100 parts of cellulose containing about 5% of moisture into a mixture containing glacial acetic acid and about 10 parts of concentrated sulfuric acid, and allowing the 70 materials to react, and thereafter introducing an acetylizing agent, while the mixture containing the sulfuric and glacial acetic acids and the acetylizing agent are at a temperature not above ordinary room temperature.
8. A process of producing cellulose acetates, substantially insoluble in chloroform and in alcohol, in a direct manner, which comprises mixing together 800 parts of glacial acetic acid and 20 parts of concentrated sulfuric acid, and introducing thereinto about 200 parts of cellulose containing about 5% of moisture, and thereafter adding, while maintaining the mixture at not 75 above ordinary room temperature, about 400 parts of acetic anhydrid.
9. A process of directly producing cellulose acetates substantially insoluble in chloroform and in alcohol, but readily soluble in chloroform-alcohol, which comprises reacting upon cellulose containing not more than about 6% of moisture with about double its weight of acetic anhydrid, in the presence of not more than about 25% of sulfuric acid as a condensing agent, at not above ordinary 80 room temperature.
10. A cellulose acetate which is substantially insoluble in alcohol alone and in chloroform alone, but which is readily soluble in alcohol-chloroform and in alcohol-tetra-chlorethane, said product being also soluble in acetone of a relatively high concentration, said product being further characterized in that upon being treated with an acid material, with or without the addition of water, its solubility in acetone of various concentrations is successively changed according to the duration of the reaction.
11. A cellulose acetate which is substantially insoluble in alcohol alone and in chloroform alone, but which is readily soluble in alcohol-chloroform and in alcohol-tetra-chlorethane, said product being also soluble in acetone of a relatively high concentration, said product being further characterized in that upon being treated with an acid material, with or without the addition of water, its solubility in an acetone of various concentrations is successively changed ac- 120
12. A cellulose acetate which is substantially insoluble in alcohol alone and in chloroform alone, but which is readily soluble in alcohol-chloroform and in alcohol-tetra-chlorethane, said product being also soluble in acetone of a relatively high concentration, said product being further characterized in that upon being treated with an acid material, with or without the addition of water, its solubility in an acetone of various concentrations is successively changed ac- 125
13. A cellulose acetate which is substantially insoluble in alcohol alone and in chloroform alone, but which is readily soluble in alcohol-chloroform and in alcohol-tetra-chlorethane, said product being also soluble in acetone of a relatively high concentration, said product being further characterized in that upon being treated with an acid material, with or without the addition of water, its solubility in an acetone of various concentrations is successively changed ac- 130

cording to the duration of the reaction, and that by further continuing said treatment, it produces a product soluble in water.

12. A cellulose acetate which is insoluble in chloroform alone, and insoluble in alcohol alone, but soluble in concentrated acetone alone, and readily soluble in a mixture of

chloroform and alcohol, said product being further characterized in that upon being treated with an acid material, a product is 10 produced having a different behavior toward acetone of various concentrations than has the product of departure.

HENRY DREYFUS.
